Arthur Frankenstein
by Philipp Lange von Hennig

UNITED STATES PATENT OFFICE.

ARTHUR FRANKENSTEIN, OF NEW YORK, N. Y.

GARMENT-SUPPORTER.

1,242,932.

Specification of Letters Patent.

Patented Oct. 16, 1917.

Application filed June 22, 1917. Serial No. 176,297.

To all whom it may concern:

Be it known that I, ARTHUR FRANKENSTEIN, a citizen of the United States, residing at New York, county of New York, and 5 State of New York, have invented certain new and useful Improvements in Garment-Supporters, fully described and represented in the following specification and the accompanying drawings, forming a part of 10 the same.

This invention relates to improvements in garment supporters and particularly to hosiery supporters.

It is well known to those skilled in the art that where elastic webbing is stitched in securing the various parts of a garment supporter together, the stitching cuts the rubber of the webbing as soon as the latter is subjected to any strain, so that the life of 20 such a garment supporter is very short.

Many attempts have been made heretofore to provide a garment supporter and particularly a hose supporter in which such stitching would be avoided or at least materially reduced. In some cases this difficulty was avoided by avoiding as much as possible the use of elastic webbing, some, 25 of course, always being necessary. This however, is disadvantageous to the wearer, 30 as thereby the elasticity of the device as a whole is materially reduced and undue strains are brought on those parts which are of elastic material. Also, attempts have been made to unite parts of elastic webbing, 35 by special metallic devices such, for example, as special buckles. Such special devices, however, are expensive, complex, increase the weight of the supporters and are likely to chafe the wearer. For reasons of 40 this kind, supporters of this kind have not been satisfactory in practice.

The object of the present invention is to provide a device by which all stitching of elastic webbing will be avoided while at the 45 same time permitting free use of such elastic material for the necessary parts of the supporter and avoiding any disadvantageous results.

With these general objects in view and 50 some others which will be obvious to those skilled in the art from the description hereinafter, my invention consists in the features, details of construction and combinations of parts which will first be described 55 in connection with the drawings and then more particularly pointed out.

In the drawings,—

Figure 1 is an elevation partly broken away of a completed device embodying the inventive features.

60

Fig. 2 a section on the line 2—2 of Fig. 1.

Fig. 3 a section on the line 3—3 of Fig. 1.

Fig. 4 a section on the line 4—4 of Fig. 1.

Fig. 5 a section on the line 5—5 of Figs. 1 and 3.

65

Fig. 6 a detail perspective view of one of the clasps G, and

Fig. 7 a similar view of one of the clips or clasps I.

Referring to the drawings, A is a supporting strap, which, for the purposes of this description, may be termed the main or adjustable supporting strap. It is advantageous in a hosiery supporter such as shown to make this main supporting strap 70 of elastic material such, for example, as elastic webbing.

B indicates a supplemental supporting strap, there being two in the garment supporter shown in the drawings, these supplemental straps being made of elastic webbing and most advantageously of one continuous piece.

C indicates a button tab, there being one for each strap B. Each button tab C is 85 made of non-elastic material and is provided with a button D secured to the tab in any suitable way. In the present example the button is carried by a clasp device E of usual construction, through openings in 90 which the button tab B is passed, the end of the tab being folded toward the front and stitched down to hold the clasp device E against shifting.

At F is illustrated a button loop. This 95 may be of any desired construction. As shown, it is made of sheet metal with the usual key-hole opening to receive the button-head and that portion of the garment which is over the head.

At the upper end, the button loop is provided with a transverse slot or opening through which the end of the corresponding supplemental supporting strap and the button tab may be passed, as more fully explained hereinafter.

Because of this slot or opening, a bar is formed at the upper end of the button loop F, as indicated at f, around which the ends of the corresponding supplemental supporting strap and button tab are folded.

The manner of attaching the button loop

F to its supplemental supporting strap B and at the same time securing the button tab C in place is as follows:

5 The upper end of the button tab and the lower end of the corresponding supplemental supporting strap B are placed back to back and substantially in register with each other. The two ends are then passed over the front of the bar f of the button loop F, thence backward through the opening or slot in the top of the button loop and then are folded upward behind the bar f and against the back of the supplemental supporting loop.

10 15 These two ends are secured in place by means of a metallic clasp G which comprises a front portion g, two side portions g' and two rear end portions g² arranged to be bent down into contact with the folded fabrics.

20 25 If desired, these end portions g² may be provided with teeth which enter the fabric.

After the ends have been fastened by the clasp G, the button tab is folded down over the end portions g² so that the latter cannot come into contact with the body of the wearer.

30 35 The connection between the supplemental supporting straps and the main supporting straps, in the best embodiment of the invention, is made as follows:

The supplemental supporting straps are formed by one piece of webbing which is folded at the desired place this fold passing over a bar h of a buckle H, which has a hinged member h' provided with teeth.

40 45 The main supporting strap is extended downward through the usual buckle opening and is arranged to be clamped at any desired point by the hinged member h'. The lower end of the main supporting strap is turned backward and upward and brought to a position in which it lies against the fold of the supplemental supporting web, over the bar h of the buckle. A metallic clip, I, advantageously U-shaped as shown, straddles the fold of the supplemental supporting strap—that is to say, rides on the cloth over the bar of the buckle—and is pressed down tightly so as to hold the fabrics or webs tightly to the bar of the buckle. In this way the supplemental supporting straps are held from sliding over the buckle-bar and also the lower end of the main supporting strap is held to the buckle.

50 55 The upper end of the main supporting strap may be provided with any suitable means for attaching it to one of the garments of the wearer, as, for example, by securing said upper end to a safety pin device such as indicated at K.

The clip I which straddles the buckle-bar is pressed so closely into the fabric which it secures, that its back portion will be buried 60 65 in the fabric and as this back portion is very

small this can readily be done, thus preventing such portion from coming into contact with the body of the wearer.

This clip also serves as a good abutment against which the web of the main supporting strap may be compressed by the hinged member of the buckle so that in this way it assists in holding the said main supporting strap against accidental shifting in the buckle. However, when the hinged member is lifted to release the main supporting strap, the latter may readily be adjusted to the desired position and then clamped at the desired point by turning down the hinged member.

70 75 80 What is claimed is:

1. In a garment supporter, the combination, with a button loop having an opening to receive a web, of a button tab and an elastic web, said tab and web having their ends inserted through the web opening in the button loop and folded back against the standing portion of the web, and a clamp clamping said ends and the standing part of the web together above the button loop, the button tab being folded back over the said two ends to cover the back of the clamp.

85 90 95 100 105 2. In a garment supporter, the combination, with a button loop having a means for holding a supporting strap, said means comprising a loop engaging bar, of a supporting strap of elastic webbing and a button tab, said strap and tab having their ends laid together and folded back to form a loop through which the loop-engaging bar passes, and a metallic clip having its front extending across the front of the elastic web above said loop engaging bar, and its ends bent around the folded end portions of the button tab and elastic web to hold said ends, the button tab being folded down over the bent end portions of the said clip.

110 115 120 125 3. In a garment supporter, the combination, with a buckle device having a web-engaging bar, of an elastic web having an intermediate portion passing around said bar, and a metallic clip arranged to clamp together the portions of elastic web at each side of said bar.

4. In a garment supporter, the combination, with a buckle device having a web-engaging bar, of an auxiliary web having an intermediate portion passing around said bar, a main supporting strap having its end laid in contact with the auxiliary web adjacent the bar, and a clip clamping together the portions of auxiliary web at each side of said bar and holding the end of said main supporting strap.

130 5. In a garment supporter, the combination, with a buckle device having a web-engaging bar, of an auxiliary web having an intermediate portion passing around said bar, a main supporting strap having its end laid in contact with the auxiliary web adja-

cent the bar, and a U-shaped clip clamping together the portions of auxiliary web at each side of said bar and holding the end of said main supporting strap.

5 6. In a garment supporter, the combination, with a buckle device having a web-engaging bar, of an auxiliary web having an intermediate portion passing around said bar, a main supporting strap having its end

laid in contact with the auxiliary web adjacent the bar, and a clip straddling the bar and clamping together the portions of auxiliary web at each side of said bar and holding the end of said main supporting strap.

In testimony whereof, I have hereunto set 15 my hand.

ART. FRANKENSTEIN.
